CLAIM

We claim the ornamental design for a lid handle, as shown and described.

DESCRIPTION

FIG. 1 is a top perspective view of a lid handle according to the new design shown within an environment in which it is used;

FIG. 2 is top perspective view of a lid handle according to the new design;

FIG. 3 is a bottom perspective view of the lid handle shown in FIG. 1;

FIG. 4 is a top plan view of the lid handle shown in FIG. 1; FIG. 5 a bottom plan view of the lid handle shown in FIG. 1; FIG. 6 is a left end elevation view of the lid handle shown in FIG. 1;

FIG. 7 is a left side elevation view of the lid handle shown in FIG. 1;

FIG. 8 is a right end elevation view of the lid handle shown in FIG. 1; and,

FIG. 9 is a right side elevation view of the lid handle shown in FIG. 1.

Features shown in broken lines form no part of the claimed design.
